DESK BASE FOR A WRITING INSTRUMENT OR THE LIKE

Donald W. Doman and Walter Irion Bieger, Janesville,
Wis., assignors to The Parker Pen Company, Janesville,
Wis., a corporation of Wisconsin

Application September 26, 1957, Serial No. 47,875

Term of patent 14 years

(Cl. D74—1)

Fig. 1 is a top plan view of a desk base for a writing instrument or the like, showing my new design;

Fig. 2 is a front elevational view thereof;

Fig. 3 is a side elevational view thereof; and

Fig. 4 is a front perspective view thereof.

We claim:

The ornamental design for a desk base for a writing instrument or the like, substantially as shown.
